Primary Examiner — Selina Sikder*(74) Attorney, Agent, or Firm* — Rabin & Berdo, PC**CLAIM**

The ornamental design for a cover lens for a light emitting diode lamp, as shown and described.

DESCRIPTION

FIG. 1 is a perspective view of the front, top and right side of a cover lens for a light emitting diode lamp showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a cross-sectional view thereof, taken on line 7—7 of FIG. 5;

FIG. 8 is a cross-sectional view thereof, taken on line 8—8 of FIG. 5; and,

FIG. 9 is a perspective view of the rear, bottom and left side thereof.

The broken lines showing an outline of a light emitting diode lamp are for illustrative purposes only and form no part of the claimed design.
